ATTORNEY.

UNITED STATES PATENT OFFICE.

HENRY C. HOOD, OF PHILADELPHIA, PENNSYLVANIA, ASSIGNOR OF ONE-HALF TO WILLIAM H. GEBAUER, OF SAME PLACE.

HEATER.

SPECIFICATION forming part of Letters Patent No. 245,498, dated August 9, 1881.

Application filed December 27, 1880. (No model.)

To all whom it may concern:

Be it known that I, HENRY C. HOOD, a citizen of the United States, residing in the city and county of Philadelphia, and State of Pennsylvania, have invented a new and useful Improvement in Heaters, which improvement is fully set forth in the following specification and accompanying drawings, in which—

Figure 1 is a top or plan view of the heater embodying my invention. Fig. 2 is a vertical section thereof.

Similar letters of reference indicate corresponding parts in the two figures.

My invention consists of a heater formed of a block of metal, heated and placed in a box with a lining or packing which completely envelops the block, said lining or packing being formed of materials which burn slowly and are ignited by the hot block, the inclosing box being afterward made approximately air-tight, as will be hereinafter set forth.

Referring to the drawings, A represents a box, which is provided with a closely-fitting lid, B, and a perforated bottom, C.

D represents a plate, which is supported on brackets or hangers D', secured to the floor of an apartment or otherwise sustained.

E represents a drum, which incloses the box A, and is open at bottom or sides, or both, a sufficiently large air-space, a, existing between the two parts, the drum being suspended from the floor of the apartment or otherwise sustained; and, if desired, the brackets or hangers D' may be bolted, riveted, or otherwise secured to the drum E.

Within the box A is a cubical or other shaped block, F, of steel or other metal of a nature that may be highly heated, and a packing or lining, G, formed of charcoal mixed with fire-clay or lime or other powdered or lumpy substance of poor conducting nature and which burns slowly. A layer of the powder is placed on the bottom of the box A, and the block F, heated to a high degree, is placed in the box on said layer, after which the side and top spaces between the block and box are also

filled with powder so that the block is completely enveloped.

The openings of the bottom C create somewhat of a draft through the powder or lining, so that the hot block may ignite the latter, and so that chilling of the block is prevented. The lid B is then applied to the box, and the box placed on the plate D of the brackets or hangers D', said plate closing the openings of the bottom plate, C, and the box being thus approximately air-tight.

It will be seen that, owing to the lining or packing G, the heat of the block F is passed off slowly, but powerfully, through the same, and the box A is kept at a high temperature, whereby the air admitted into the drum E and striking the hot box A is heated, and so passed out of the register or into the pipes which lead into the apartment or place to be warmed. As the block cools slowly it renders service for a long time. When the block requires reheating the box is opened, the top packing removed, the block withdrawn, and side packing also removed, after which the block, again heated, is placed in the box and the other operations are repeated.

I am aware that it is not new to employ a heated block of metal and an inclosing non-conducting box for the purpose of a heater, and therefore disclaim the same, broadly.

Having thus described my invention, what I claim as new, and desire to secure by Letters Patent, is—

1. The box A, in combination with a block of metal enveloped in packing of such a nature that it burns slowly, substantially as and for the purpose set forth.

2. A heater consisting of a heated block of metal enveloped in packing which burns slowly, and inclosed in a box provided with means for making it approximately air-tight, substantially as and for the purpose set forth.

H. C. HOOD.
